UNITED STATES PATENT OFFICE.

CHARLES H. BLANCHARD, OF BATAVIA, OHIO.

AUTOMATIC FAN.

SPECIFICATION forming part of Letters Patent No. 271,211, dated January 30, 1883.

Application filed October 13, 1882. (No model.)

To all whom it may concern:

Be it known that I, CHARLES H. BLANCHARD, of Batavia, Ohio, have made a new and useful Improvement in Automatic Fans, of 5 which the following is a full, clear, and exact description, reference being had to the annexed drawings, making part of this specification, in which—

Figure 1 is a view in perspective of the improvement in position; and Figs. 2 and 3, details, being sectional views taken through the casing. Fig. 2 shows the arrangement when a cord and weight are used, and Fig. 3 when a spring is used.

15 The same letters denote the same parts.

The present invention is an improvement in fans used to agitate the air in sleeping-apartments, sitting and dining rooms, workshops, and other places, and for driving away flies, 20 mosquitoes, &c.

It consists of a revolving fan actuated by a cord and weight, the fan being connected with a casing or frame containing gearing for operating the fan, and the fan and casing being suspended by a vertically-adjustable connection from an overhead support.

A, Fig. 1, represents the fan, having one or more vanes, *a a*. It is attached to a shaft, *B*, which in turn is supported in or upheld by a 30 casing or frame, *C*. This casing or frame is suspended from an overhead fixture—say, the ceiling *D*.

The suspending device *E* is constructed so as to make the fan vertically adjustable; and 35 to this end the suspensory *E* may be in two parts, *e* and *e'*, the lower part, *e*, being movable upward and downward upon the upper part,

e', and fixed at any point thereon by means of the set-screw *e²*.

A weight, *F*, is suspended from a cord, *G*, 40 which passes over bearings *H H*, and thence around a drum, *I*, upon the shaft *J*. This last-named shaft rotates in bearings in the casing *C*, and a train of wheels, *K L*, communicates the motion of the shaft *J* to the fan-shaft *B*. 45

In operation, the weight *F*, by applying a key to the shaft *J* at *j*, is wound up toward the ceiling *D*, and on releasing the weight (which can be done in any of the usual ways) the shaft *J* is set in motion, and the fan in consequence 50 to rotating. Fringes *M*, attached to rods *m m*, may be hooked to the vanes *a a*. A spring, as in Fig. 3, may be used in place of the weight and cord to drive the shaft *J*.

I claim—

1. The combination of the revolving fan *A*, the shaft *B*, the casing *C*, the vertically-adjustable suspensory *E*, the weight *F*, the cord *G*, the drum *I*, the shaft *J*, and the train *L K*, substantially as described. 55

2. The combination of the revolving fan *A*, the casing *C*, the shaft *B*, and the rods *e e'*, the rod *e* being vertically adjustable upon the rod *e'*, substantially as described. 60

3. A revolving fan, *A*, actuated by a train 65 of gearing, said fan and train having a vertically-adjustable connection with an overhead fixture, *D*.

4. The revolving fan *A*, having the removable fringes *M*, as and for the purpose described. 70

C. H. BLANCHARD.
